CLEAVER

Jerome P. Mills, Milwaukee, Wis.

Application January 17, 1950, Serial No. 7,291

Term of patent 7 years

(Cl. D44—29)

To all whom it may concern:

Be it known that I, Jerome P. Mills, a citizen of the United States of America and a resident of Milwaukee, in the county of Milwaukee and State of Wisconsin, have invented a new, original, and ornamental Design for Cleaver, of which the following is a specification, reference being had to the accompanying drawing, forming a part thereof.

In the drawings:

Fig. 1 is a side elevational view of a cleaver embodying the invention;

Fig. 2 is a top view of the cleaver shown in Fig. 1; and

Fig. 3 is a cross-section taken on the line 3—3 of Fig. 1, looking in the direction of the arrows.

I claim:

The ornamental design for a cleaver, as shown.
JEROME P. MILLS.
